HULL CONSTRUCTION

Alfredo Berardinelli, Genoa, Italy

Application July 28, 1931, Serial No. 553,637
In Italy July 29, 1930

3 Claims. (Cl. 114—79)

The present invention relates to improvements in the construction of lightweight hulls, particularly suitable for small ships capable of high speeds, or hydroplanes.

5 The preferred practical application of this invention embodies a main framework, a secondary framework and an exterior skin consisting of relatively thin plates. The main framework consists of longitudinal and transverse girders arranged and proportioned to resist substantially all longitudinal and transverse stresses independently of the exterior skin. The secondary framework consists of stringers suitably arranged to give further support to the thin plates 10 and to supplement the latter in resisting local stresses resulting from pressure and shock.

In practicing my invention, the secondary framework serving as supporting and reinforcing means for the plates, also constitutes means 20 for attaching the plates to the main framework.

The main framework comprises a system of light longitudinal and transverse members arranged to resist substantially all longitudinal and transverse stresses independently of the external plating. The skin of the hull, that is, the bottom, sides and deck plating, is subdivided 25 into plates of suitable thickness and dimensions, which are arranged to suit the particular requirements of each type and size of hull. Depending on the function and location of each 30 plate, the secondary structure may comprise: a system of light longitudinal and transverse members assisting the external plating in resisting local hydrodynamic and impact stresses, means for joining the plates together so as to 35 form a continuous water-tight skin, means for securing bulk heads within the framework, and finally means for securing each plate to the main framework.

40 Among the advantages afforded by the present invention, are the following:

1. The plates constituting the skin of the hull may be made of any ordinary material instead of special metals.

45 2. A hull constructed in accordance with my invention has a high resistance to stresses as the latter are taken up by continuous members.

3. A hull constructed in accordance with my invention has a stronger and smoother exterior 50 skin due to the elimination of external riveting.

55 4. My invention makes possible the construction of the hull in different places and at different times, that is, the plates and the elements constituting the framework may be constructed at one place and time, and the hull may

be assembled from these materials at another time and place.

5. The simplified construction embodied in my invention will lower production costs, as the component parts are reduced to a few distinct elements which can be suitably standardized irrespective of the type of hull to be constructed.

6. A hull constructed according to my invention permits the use of ordinary steels suitably coated to prevent corrosion and eliminates the necessity of making the plates of special and more expensive alloys.

7. The present construction of the hull renders all parts easily accessible for inspection and maintenance, and facilitates local repairs 10 to the hull and the replacing of defective or damaged plates.

The accompanying drawings illustrate, by way of example, the practical embodiment of the invention, in which the same letters or numerals 20 identify the same parts throughout.

Figure 1 represents a partial plan view of the bottom of a hull, which for simplicity is assumed to be flat;

Fig. 2 is a plan view of part of the skin of 25 the hull, the main framework, and the secondary framework in assembled condition;

Fig. 3 is a section taken along lines III—III of Fig. 2;

Fig. 4 is a section along lines IV—IV of Fig. 30 2; and

Fig. 5 is a side view of a lattice girder designed to take up the longitudinal strains of the hull.

Referring to the practical embodiment of my 35 invention illustrated in the drawings:

The skin of the hull is composed of a plurality of thin plates, *a*, *b*, *c*, *d*—*d*, *e*, *f*, *g*—*e*, *f*, *h*, *i*—*b*, *c*, *j*, *l*—*i*, *h*, *m*, *n* etc.

The hull is suitably divided by bulk heads 1. 40

The secondary framework of the hull comprises stringers 4, 5, 6 and 8.

The main or primary framework comprises transverse latticed girders 2, lighter intermediate girders 3, and longitudinally extending latticed girders 7. Girders 2 are provided with top members 9. Angle irons 10 are provided to connect the external plating with the divisional bulk heads 1.

50 The plates *a*, *b*, *c*, *d* etc. are made of any suitable size. These plates are secured to the secondary framework by electric welding to avoid an irregular or broken outer surface. The edges of the plates do not overlap but meet on and are electrically welded to the outer flanges of 55

the stringers 5, 6 and 8. Stringers 4 are positioned intermediate the edges of the plates and are suitably electrically welded thereto, for example, at intervals.

5 Transverse girders 2, 3 of the main framework are secured to the inner flanges of stringers 4, 5 and 6 by riveting and/or welding.

The upstanding flange of stringer 3 may be suitably secured to the latticed girders 7.

10 Girders 2 are arranged at suitable distances apart. Intermediate girders 3 are arranged closer together.

15 Stringers 4 are intended to give further support to the plates and to supplement the latter in resisting local stresses resulting from shock and pressure.

20 Stringers 5, 6 and 8 serving as boundary members for the plates constituting the skin of the hull assist the plating in resisting local hydrodynamic and impact stresses. These stringers also serve as means for connecting each plate to the adjacent ones so as to form a continuous water-tight skin for the hull, and means for connecting each plate to the main framework.

25 The main framework comprising girders 2, 3 and 7 are connected by riveting and/or welding to form a rigid structure proportioned to resist substantially all longitudinal and transverse stresses independently of the external plating, which can thus be made very thin.

30 The component parts of the hull may be fabricated as follows: the external plating constituting the skin of the hull is first developed and cut into portions of suitable dimensions, after which it is assembled into panels by electrically welding the secondary framework to each plate. If desirable, these panels may be electrolytically plated to prevent corrosion. The elements comprising the main framework, such as the keel, 35 longitudinal girders, transverse girders and bulk heads are assembled into a complete internal structure on which the panels comprising the outer skin are then superimposed by connecting the various stringers comprising the secondary 40 framework to the adjacent members of the main framework by means of riveting and/or welding. The preferred method of securing the assembled 45 secondary framework and plating to the main framework consists in riveting or welding the flanges of the stringers to the flanges of the adjacent members of the main framework with the faces of the respective flanges in abutting relation as shown, for example, in Fig. 3. The 50 plates are preferably arranged in rows, the plates in each row being staggered with respect to the plates in the adjoining row.

55 In general, continuous line welding is preferred in securing the plates to the stringers constituting the boundary members, to make sure that the external skin will furnish a water-tight covering for the hull. Spot welding may be used to connect the intermediate stringers 4 to the plating. Spot welding or riveting may be used

to connect the secondary framework to the main framework. Riveted connections may be used in the main framework. With this construction, the outer skin will not be perforated by rivets so that its strength will be unimpaired and will have a smooth external surface offering less frictional resistance to the exterior fluid.

5 Although for descriptive reasons the present invention has been based on the preceding specification and on the accompanying drawings, yet 10 many practical modifications may be made in the solution of the problem, all these modifications being based on the fundamental principles of the invention as set forth in the following claims.

15 Having now particularly described and ascertained the nature of my said invention and in what manner the same is to be performed, I declare that what I claim is:

1. A hull construction comprising a main 20 framework having longitudinally and transversely extending flanged members, a secondary framework of flanged stringers, and an exterior skin consisting of a plurality of panels formed of thin plates reinforced by said stringers, said panels being fastened to said main framework by securing the flanges of said stringers to the flanges of the adjacent members of the main framework with the faces of the respective flanges in abutting relation.

30 2. A construction for light hulls, suitable for ships, hydroplanes and the like, comprising a main framework consisting of a plurality of continuous main longitudinal girders and transverse frames, said girders and frames being 35 provided with flanges running along the faces of the hull, a secondary framework of flanged stringers, and an outer skin subdivided into panels formed by thin plates reinforced by said stringers in closely spaced relation and welded to said plates, said panels being fastened to said framework by welding the flanges of said stringers to the flanges of the adjacent girders and frames with the faces of the respective flanges in abutting relation.

40 3. A hull construction comprising a main framework having longitudinally and transversely extending flanged members arranged and proportioned to resist substantially all longitudinal and transverse stresses set up in the hull, and an external skin for the hull composed of a plurality of thin plates, each of said plates being reinforced by flanged stringers interposed between said main framework and said skin and arranged to give further support to the skin and to supplement the latter in resisting local stresses resulting from pressure or shock, the stringers and the members of the main framework being secured together through their flanges with the faces of the flanges in abutting 50 relation.

45 55 60 ALFREDO BERARDINELLI.
